UNITED STATES PATENT OFFICE.

WILLIAM J. SPRANGERS, OF HOLLAND, WISCONSIN.

SHUTTER OR DOOR.

SPECIFICATION forming part of Letters Patent No. 585,239, dated June 29, 1897.

Application filed April 5, 1897. Serial No. 630,779. (No model.)

To all whom it may concern:

Be it known that I, WILLIAM J. SPRANGERS, a citizen of the United States, and a resident of Holland, in the county of Brown and State 5 of Wisconsin, have invented certain new and useful Improvements in Shutters or Doors; and I do hereby declare that the following is a full, clear, and exact description thereof.

My invention has for its object to provide 10 an outside shutter or door that may be utilized in summer as an insect-screen and in winter as a weather-shield. Therefore it consists in certain peculiarities of construction and combination of parts hereinafter set forth 15 with reference to the accompanying drawings and subsequently claimed.

Figure 1 of the drawings represents a side elevation of a shutter constructed according 20 to my invention and partly broken away; Fig. 2, a vertical section viewed on the plane indicated by line 2 2 in Fig. 1, and Fig. 3 a horizontal section indicated by line 3 3 in Fig. 1.

Referring by letter to the drawings, A represents a perforated plate of sheet metal having portions thereof bent upon a preferably 25 metal frame B and riveted thereto, the edges of the plate being turned inward to abut the frame, as herein shown.

Opposing the plate A between the latter and its recurved edges is another perforated sheet-metal plate C, the latter having adjustment to bring its perforations in or out of 30 register with those in the former plate, as hereinafter more fully described.

To provide for adjustment of plate C, the latter is of less dimension in one direction thereof than the inside of the frame B, as clearly illustrated in Fig. 2, and the plate A 40 is provided with slots b in the direction of the adjustment, these slots serving as guides for screws c d, connecting said plate C and a bar D, the latter having play on the outside of the stationary plate. Washers are interposed between the plate C and heads of the 45 screws c d, and the head of the latter screw

is shown provided with wings e, by which said screw may be readily operated to clamp said plate C in adjusted position against the one on which it slides.

When the perforations of plate C are brought into register with those of plate A, the shutter or door serves to admit outside air and at the same time exclude insects, but if a reverse adjustment of said plate be had 55 the structure of which it forms a part will exclude weather when in closed position in a casing to which it may be hinged.

The blind or door above specified being preferably metal throughout it is fireproof 60 and very durable.

Having thus described my invention, what I claim as new, and desire to secure by Letters Patent, is—

1. A shutter or door comprising a frame, a 65 perforated plate of sheet metal made fast to the frame and having recurved edges abutting the same, another perforated but movable sheet-metal plate opposing the one aforesaid between the latter and its recurved 70 edges, and suitable means for effecting adjustment of the movable plate to bring its perforations in or out of register with those in the stationary plate.

2. A shutter or door comprising a frame, a 75 slotted and perforated plate of sheet metal made fast to the frame and having recurved edges abutting the same, another perforated but movable sheet-metal plate opposing the one aforesaid between the latter and its re- 80 curved edges, a slide-bar outside the stationary plate, and screws that have play in the slots of the latter plate but connect the movable plate and slide-bar.

In testimony that I claim the foregoing I have hereunto set my hand, at Holland, in the county of Brown and State of Wisconsin, in the presence of two witnesses.

WILLIAM J. SPRANGERS.
